Attorneys.

UNITED STATES PATENT OFFICE.

FRANK L. GLOVER, OF INDIANAPOLIS, INDIANA, ASSIGNOR TO GLOVER EQUIPMENT COMPANY, OF INDIANAPOLIS, INDIANA, A CORPORATION OF INDIANA.

DASH-OPERATED AUTOMOBILE-RADIATOR COVER.

1,197,817.

Specification of Letters Patent. Patented Sept. 12, 1916.

Application filed December 27, 1915. Serial No. 68,860.

To all whom it may concern:

Be it known that I, FRANK L. GLOVER, a citizen of the United States, residing at Indianapolis, in the county of Marion and State of Indiana, have invented certain new and useful Improvements in Dash-Operated Automobile-Radiator Covers, of which the following is a specification.

The object of this invention is to provide a radiator hood for motor vehicles which may be set to retain the heat when the engine of the vehicle is standing idle, and which may be readily adjusted to a more or less open condition when the engine is running and also when the engine and vehicle are running.

Another object is to provide means whereby this adjustment may be readily made by an operator while seated in the vehicle, thereby obviating the inconvenience, particularly where self-starters are used for starting the engine without hand cranking, of going to the front of the machine where the radiator is located.

25 A further object of the invention is to provide a simple and durable device of the above character, which can be manufactured at small cost and installed easily on any of the motor vehicles now in use.

30 I accomplish the above objects by the mechanism illustrated in the accompanying drawing, in which—

Figure 1 is a perspective view of a motor vehicle hood and radiator with my invention applied in operative position thereto. Fig. 2 is an elevation of the rear side of the dash shown in Fig. 1. Fig. 3 is a horizontal section of my improved hood on the line 3—3 of Fig. 1, detached from the radiator and on a larger scale than in Fig. 1. Fig. 4 is a section the same as Fig. 3 of a portion only on a still larger scale, and Fig. 5 is a view in side elevation of the hood detached from the radiator.

45 Like characters of reference indicate like parts throughout the several views of the drawings.

The hood portion comprises essentially a front member having radial openings which are more or less closed by a damper, and a member at right angles to the front, which contacts the top and sides of the radiator. Said front member comprises a sheet metal plate 6 of slightly less area than the full front, which is assembled between two, fab-

ric or leather sheets 7 and 8 of the full area of the front, and is held in position between the latter by stitching the sheets 7 and 8 together at the margin of the metal plate 6 as shown by the dotted line 9, Fig. 1. The member covering the top and sides of the radiator comprises a double thickness of fabric or leather 10, 10, between which is a filling 11, of asbestos or other non-conductor of heat, all of said parts being united by 55 stitches indicated by the dotted lines 12, 13 and 14. This member is united with the member for the front of the hood by a hinge-strip 15, which is preferably a single thickness of fabric or leather sewed to both 60 of them by stitches indicated by the dotted line 14 and 16. This provides a flexible hinge which affords an appreciable range of adjustment between said two principal members which enables the hood to be applied to radiators varying somewhat in size and shape, and is a matter of much importance in a commercial sense as it enables me to fit a wider range of motor vehicles with a smaller assortment of hood-sizes than 65 would otherwise be possible.

The member covering the top and sides of the radiator is reinforced at the top with a member 16', for additional strength where the material is cut out for the passage of 70 the radiator cap. The bottom of the hood is secured in front by a pair of straps 17 which buckle around the crank shaft 18, and it is secured at the sides by wires 19, having loops at one end by which they are 75 riveted to the side members of the hood. These wires are bent around a lamp-post, bolt or any conveniently projecting portion of the frame of the car.

To provide ventilation through the front member of the hood,—that is, a circulation of air to and through the radiator to cool its water contents, I provide openings 20 which radiate from the neighborhood of the center of the front member of the hood. The center is left intact to support a bolt 21 of a damper 22, which oscillates on said bolt. The damper comprises a metal plate 23 which is covered on both sides by a layer of leather or fabric 24, 24, stitched together 80 around the margin of the plate. This damper has slots corresponding in size shape and location with the openings 20 of the front member of the hood, and the slots of 85 the two members will be brought more or 90 front member of the hood, and the slots of 95 the two members will be brought more or 100 front member of the hood, and the slots of 105 the two members will be brought more or 110 front member of the hood, and the slots of

less into register by a rotary adjustment of the damper to regulate the size of the air passages.

While the damper may be moved by hand by an operator standing close to the radiator, I have provided means for adjusting from the back of the dash. This comprises a rod 26 which passes through the dash 27 and through the hood 28, and thence through 10 the radiator (through one of the ventilator openings therein) and through the front member of the hood. A crank-arm 29 on the projecting front end of the rod is connected by a link-bar 30, with a pin seated in 15 the damper 22. On the other end of the rod 26 is a lever 31, preferably of resilient metal which is strained to cause the lever to contact the notches of a segmental rack 32, between it and the dash. By rocking the rod 26 the damper 22 may be partially rotated to open or close the front openings in the hood, and any given adjustment may be

retained by engagement of the lever 31 in its rack.

Having thus fully described my invention what I claim as new and wish to secure by Letters Patent of the United States, is—

A supplemental hood for motor-car radiators comprising a front member formed of two flexible sheets and a metal sheet of less area secured by stitching the flexible sheets together at the margin of the metal sheet, a member for the top and sides of the radiator comprising a pair of flexible sheets and a sheet of nonconducting material between them, and a hinge member of flexible material connecting said last member with said front member.

In witness whereof, I, have hereunto set my hand and seal at Indianapolis, Indiana, this 3d day of December, A. D. one thousand nine hundred and fifteen.

FRANK L. GLOVER. [L.S.]
